(57) **CLAIM**

The ornamental design for a cosmetic dispenser with cap, as shown and described.

DESCRIPTION

FIG. 1 is a perspective view of a cosmetic dispenser with cap, showing my new design;

FIG. 2 is a side view thereof, with opposite side, front, and back views being the same;

FIG. 3 is a top view thereof, shown in enlarged scale;

FIG. 4 is a bottom view thereof, shown in enlarged scale; and,

FIG. 5 is a cross-section view thereof, taken along line 5-5, of FIG. 2.

The broken lines in the figures illustrate the portions of the design that form no part of the claimed design.

1 Claim, 5 Drawing Sheets
